ISADORE COHEN, OF BROOKLYN, NEW YORK, ASSIGNOR OF ONE-HALF TO LANDSBERG
BROTHERS, OF NEW YORK, N. Y.

MACHINE FOR FORMING AND SETTING WIRE STAPLES.

1,181,846.

Specification of Letters Patent.

Patented May 2, 1916.

Application filed October 16, 1914. Serial No. 866,948.

To all whom it may concern:

Be it known that I, ISADORE COHEN, a subject of the Czar of Russia, residing at Brooklyn, in the county of Kings and State 5 of New York, have invented certain new and useful Improvements in Machines for Forming and Setting Wire Staples, of which the following is a specification.

The present invention relates to improvements in machines for forming and setting wire staples and has for its object to provide a device of this class which is simple in construction, cheap to manufacture and efficient in operation, and in which the formation and setting of the staple and the feeding of the wire is accomplished by a single stroke of a manually operated lever.

My invention is illustrated in the accompanying drawings, in which similar reference characters denote corresponding parts 20 and in which—

Figure 1 is a front elevation of device; Fig. 2 a vertical section on line 2—2 of Fig. 1; Fig. 3 a vertical section on line 3—3 25 of Fig. 2; Fig. 4 a section similar to Fig. 3, somewhat enlarged and with the frame and the actuating means removed, and Fig. 5 is a rear view of the member carrying the cutting blade and of the member carrying 30 the resilient anvil over which the wire is bent into a staple.

Specifically referring to the drawings, *a* denotes the base which carries the frame *b* formed with a lateral bracket *b'* supporting 35 a cylindrical magazine *c* which is open in front. Revolvably borne in this magazine on a central spindle or pin *d'* is a spool *d* on which the wire *e* is wound. The free end of the wire is passed outwardly from the 40 magazine through a passage *c'* in the periphery of the magazine. A spring brake *d''* for the spool is hinged to the magazine at *d''* and presses against the outer face surface 45 of the spool *d*. The opposite free end *d''* of the spring brake *d''* engages by friction or otherwise with the circumference of the magazine *c*. Projecting forwardly from the upper end of the frame is a headed pin *f* which serves as a fulcrum for a manually 50 operated cam lever *g* whereby the machine is operated. In front and below the pin *f* the frame is provided with a vertical groove *b''* in which is slidably borne a member *i* formed at its top with a boss *i'* and at its

bottom with a forwardly extending projection *i''* which serves as a staple driver. The forward edge *i''* of the staple driver is cam-shaped or slanting for the purpose herein-after explained.

Covering the space *i''* formed between the out- 60 boss *i'* and the staple driver *i''* from the outside or front is an independently movable member *j* which at its bottom is formed with an enlarged projection or boss *j'* that ex- 65 tends into the said space *i''* above the staple driver and between which and the boss *i'* a spring *k* is provided, whereby the member *j* is yieldingly supported in the groove or re- 70 cess *b''* of the frame, and in the range of the cam-shaped surface *g'* of the cam lever *g* by which it is operated. The member *j* on 75 the other hand has a link connection *h* with the cam lever *g*, one end of said link *h* being fastened at *h'* to the upper end of the member *j* and the other end thereof being 80 slotted at *h''* to engage a pin *h''* projecting from a point located away from the center of the fulcrum *f*. Normally, that is when the parts are in their initial position, the link *h* extends in vertical direction as shown 85 in Fig. 1. The member *j* is provided with two legs or downward extensions *j''* project- 90 ing below and at the sides of the boss *j'*, and which at their opposite inner edges and at their lower edges are provided with longitudi- 95 nal grooves *j''*, *j''* respectively. The leg located on the side of the wire magazine at the corner of the outer and lower edges is provided with a sharpened projection *j''* which serves as a cutting edge or blade. 100 Provided with an inner or rear vertical groove *l''* forming a guideway for the member *j* and its legs or extensions *j''* is a plate *l* which is fixed to the frame by screws *l'*. This plate serves to hold the members *i* and *j* in proper position within the groove *b''* of the frame, and also as a support for a mem- 105 ber *m*. The latter is formed at its lower end and on its rear with a projection or block *m''* which is adapted to serve as an anvil over which the wire *e* is bent into a staple. The member *m* at *m''* is yieldingly supported on the plate *l* so as to be capable of a slight forward and backward movement and the anvil or projection *m''* is adapted to normally 110 extend through a recess *l''* inwardly so as to extend in the path of the member *j* and through the space *j''* formed between the legs

j² thereof. Above the block or anvil *m²* the member *m* is provided with a cam or tooth-like projection *m³* with which the projection *i⁴* or the staple driver *i²* is adapted to operate during the depression of the member *i* to push the member *m* forwardly and to thereby release the staple *e'* formed of the wire *e* in the manner to be hereinafter more fully described. The tiltable or yielding member *m* is pressed into the normal vertical position by a suitable spring *m⁴* which is fixed to the plate *l* by the screws *l'*. The plate *l* is provided with a tubular opening *l³* extending transversely from the side 10 facing the wire magazine toward and about in line with the upper surface of the anvil, this opening serving as a passage for the wire *e* coming from the magazine.

Arranged on the base *a* in the path of the legs or extensions *j²* of the member *j* and also of the staple driver *i²* is a clenching block *b²* which in conjunction with the latter serves to clench the legs of the U-shaped staple.

20 The feeding of the wire is accomplished by a toothed spring actuated pawl *o* which is carried by a lever *o'*. The latter is fulcrumed to the frame at *o²* and its free end *o³* is cam-shaped engaging a correspondingly shaped groove *g²* of the cam lever *g*. A spring actuated clamping cam *n* serves to grip the wire to hold it in position during the operation and prevent it from being drawn away from the anvil *m²*.

30 The operation of the device is as follows: By turning the lever from the position shown in Fig. 1 the feeding lever *o'* will be swung from the full line position into the dotted line position thereby causing the pawl *o* to feed the wire a given length and the wire *e* to pass through the opening *l³* across the anvil *m²*. The stroke of the pawl *o* corresponds to the width of the space *l²* across which extends the piece of wire to be cut off and bent into a staple. During 40 this first fraction of movement of the cam lever *g*, the member *j* will be caused by the link *h* to move down and to sever the piece of wire by its cutting edge *j⁴*. A continuation of the movement of the lever *g* in the same direction will cause the legs *j²*, engaging the wire in their lower grooves *j⁵* to bend the severed piece of wire at right angles on both sides of the anvil *m²*, thereby 50 forming a U-shaped staple *e'* and in this operation the vertically bent parts of the severed piece of wire will engage the lateral grooves *j⁶* in the legs *j²*. A further continuation of the movement of the lever *g* will cause the staple driver to expel the boss *i'* of the member *i* and thrust the latter downwardly, bringing the staple driver into contact with the staple after its cam-shaped projection *i⁴* has tilted the yielding member 60 *m* forwardly, and its anvil *m²* released the

staple. A further movement of the lever *g* will cause the staple driver to expel the staple from the legs *j²* and press it against the stationary clenching block *b²* and through the sheets of paper *p* held across the latter, whereby the vertical parts of the staple *e'* will be bent toward one another or clenched, thereby fastening the papers. (Fig. 3). It is thus seen that a single throw of the lever from the full line position into the dotted line position will operate successively the feeding mechanism, cutting and forming mechanism and the staple driver. During the first part of the movement of the lever *g* the feeding lever *o'* will receive its given throw and will remain stationary during the rest of the movement, while its free end is sliding on the circular portion *g³* of the lever. The return movement of the lever from the dotted line position into full line position will first release the member *i*, then through the link *h* raise the members *i* and *j* into initial position, releasing the anvil *m²* and permitting it to return into its normal position and finally the recess or groove *g²* will engage the upper end of the feeding lever *o'* tilting it from its dotted line position into full line position to cause its toothed pawl *o*, which, during the return movement, will slide freely along the wire, to clamp the latter for the next feed.

The part *q* on the base denotes an adjustable gage to enable the holding of the sheets of paper to be fastened in proper position across the clenching block *b²*.

The plate *l* is cut out at *l⁶* to accommodate the gripping member *n* and the upper edge of the said recess is grooved as at *l⁵* to expose the wire *e* passing through the opening *l³* to the action of the grip *n*. The opposite inner side of the plate *l* is grooved as at *l⁴* so that when the plate is fixed in position an opening is left between the plate *l* and the frame *b* through which the piece of wire which accidentally may have become twisted without forming a staple will be fed outwardly.

Since the device may be variously modified without deviating from the principle of my invention, I do not restrict myself to the details shown and described.

In order to make the action of the cutting member *j* a positive one, an additional cam portion *g⁴* is provided on the cam lever *g* which is arranged at such a point that during the first fraction of rotation of the lever *g* it will engage the upper edge of the member *j* and force the latter downwardly thereby causing the cutting edge *j⁴* to sever the wire.

What I claim and desire to secure by Letters Patent is:

1. In a device for forming and setting wire staples, the combination with wire feeding means, of a resiliently mounted an-

- vil, a vertically movable member formed with a cutting edge to cut the wire and having means to bend the severed piece of wire at right angles on both sides of said anvil, 5 a spring carried by said member, a vertically movable staple driver supported on said spring and having means to actuate said anvil so as to release the staple from the latter, a clenching block below said staple driver, the latter being arranged to thrust said staple against said clenching block and to clench it, and manually operated means for operating said wire feeding means, said movable member and said 10 driver successively.
2. In a device for forming and setting wire staples, a resiliently mounted anvil, a vertically movable member having downwardly extending legs serving to bend the wire across said anvil into a staple, and a cutting edge on one of said legs to sever said wire, a vertically movable staple driver having means to actuate said anvil so as to release the said staple from said anvil and 15 arranged to thrust the staple downwardly, a spring carried by said member for supporting said staple driver, means coöperating with said staple driver to clench the staple, and a manually operated cam lever 20 for operating said wire feeding means, said movable member and said driver successively at a single throw.
3. In a device for forming and setting wire staples, the combination with means for feeding the wire, of a swinging lever carrying said means, a resiliently mounted anvil, means for cutting the wire and bending the severed piece of wire around said anvil into a staple, a staple driver to thrust the 25 said staple outwardly and to assist in clenching it, a spring carried by said last named means to support said staple driver, and a manually operated cam lever operatively connected to said first lever and arranged at 30
- a certain position to engage and positively 45 actuate said staple driver.
4. In a device for forming and setting wire staples, the combination with a manually operated cam lever, of a member operatively connected to said cam lever and 50 formed with downwardly projecting legs and a cutting edge, a spring carried by said member, a staple driver formed with a boss arranged in the path of said cam lever and resting on said spring, a resiliently mounted 55 anvil having means arranged to be acted upon by said staple driver to be moved out of the path of said member, and a clenching block with which said staple driver coöperates to clench the staple.
5. In a device for forming and setting wire staples, a frame having a vertical groove, a cam lever fulcrumed in said frame, a staple driver loosely mounted in said groove and in the path of said cam lever to 65 be engaged and positively actuated by the latter at a certain position thereof, a vertically movable member linked to said cam lever and having downwardly projecting legs and a cutting edge, a spring carried by 70 said member to support said staple driver, a resiliently mounted anvil having means arranged to be acted upon by said staple driver to be moved by the latter out of the path of said movable member, means operated from said cam lever to feed the wire across the said anvil, said legs and cutting edge serving to sever and bend the wire into a staple, and a clenching block carried on 75 said frame with which said staple driver co- 80 operates to clench the staple.

In testimony whereof I affix my signature in presence of two witnesses.

ISADORE COHEN.
